UNITED STATES PATENT OFFICE.

STEPHEN A. COVELL, OF PITTSBURG, KANSAS.

WAGON-BOX.

1,034,587.

Specification of Letters Patent. Patented Aug. 6, 1912.

Application filed May 12, 1911. Serial No. 626,812.

To all whom it may concern:

Be it known that I, STEPHEN A. COVELL, citizen of the United States, residing at Pittsburg, in the county of Crawford and 5 State of Kansas, have invented certain new and useful Improvements in Wagon-Boxes; and I do declare the following to be a full, clear, and exact description of the invention, such as will enable others skilled in 10 the art to which it appertains to make and use the same.

The invention relates to wagon-boxes.

The object of the invention is to provide a wagon-box which shall be simple of construction, durable in use, and comparatively inexpensive of production and one which has its sides constructed in three sections, the center section and end-gates so constructed that they may be readily and 20 easily removed in order to facilitate in loading and unloading the box from the ends or side sectional openings. Not only are the side sections and ends of box constructed so as to be easily removed, but so constructed 25 as to be easily and rapidly replaced.

With this and other objects in view the invention consists of certain novel features of construction, combination, and arrangement of parts, which will be hereinafter 30 more fully described, and particularly pointed out in the appended claim.

In the accompanying drawings, Figure 1 is a top plan view of the whole box. Fig. 4 is side view of entire box. Fig. 2 is a detailed perspective view with part cut away 35 showing manner in which the lower bed of center sections of sides of box are engaged with the outer sections. Fig. 3 is a detailed view with parts cut away showing construction and manner of fastening the ends of 40 box in relation to sides of box.

Like numerals of reference designate corresponding parts in the several figures of the drawings.

45 In the accompanying drawings, 1, 2, 3, and 4 are common bed supports for the bottom bed of the wagon.

50 5, see Fig. 1, is bottom of the box. 6 and 7 are lower bed end-gates, same structure. 8, 9, 12 and 13, similar structure, are outer sections of sides of the lower bed of box securely fastened to bottom of box and engaging the lower end-gates and lower box side-gates.

55 10 and 11 are lower bed side-gates engag-

ing with outer sections of sides as shown in Fig. 2.

14 and 15 are upper box end-gates similar in structure to lower bed end-gates.

16, 18, 19 and 21 are the upper side box 60 end sections engaging end-gates and side-gates similar to end-gates and side-gates in lower box, which are fully described in detail in the parts described in Figs. 2 and 3 and their connections, which is set forth 65 more specifically in the description of parts 25, 27, 26, 51, 44, 52 and 53.

17 and 20 are upper bed side-gates engaging with outer sections of sides as shown in Fig. 2. 70

22 and 23 are metal projections firmly fastened to upper end-gate, 15, extending downward fitting closely against the inner side of lower end-gates which holds top box from sliding. Both ends are equipped the 75 same.

24, 25, 26 and 27 are metal slide channels all of the same construction. See Fig. 2. These metal slide channels engage with the outer sections of the sides of box making 80 the sides firm when slipped into place engaging parts as before mentioned.

28, 29, 30, 31, 32, 33, 34 and 35 are the clamp fasteners holding top box in place.

The thumb bolts of the clamp fasteners, 85 28, 29, 30, 31, 32, 33, 34 and 35, holding the top box as above mentioned, pass through the clasp iron then through an opening provided by cutting away one half the area of the circle desired, from each the top box 90 and the lower side bed.

36 and 37 show brace irons supporting the sides 9 and 13. See Fig. 4. Opposite sides of box structure the same. These irons are shaped to give bracing power. 95

38 is a right-angled iron fastened firmly to the bottom of box and the upper portion extending up equal to the thickness of the bed of the wagon-box which strengthens the box not allowing the bed to spring and thereby bind the side-gates when the box is loaded. By this means of strengthening the wagon-bed in connection with brace irons, 100 36 and 37, the side-gates can easily be removed whether the center of box is loaded 105 heavily or not.

39 is a hook and eye rod fastened to lower side-gates preventing them from spreading when the box is loaded with such material as sand, gravel, coal, etc. 110

40, 41, 42 and 43 are guide irons forming a channel which engages with outer sections of top box, both sides of box equipped the same. See Fig. 4.

5 44, 45, 46 and 47 are key bolts keying end-gates to sides, both ends of box equipped the same. See Fig. 3.

10 48, 49 and 50 are metal strips fastened to ends of side sections and end-gates 10 strengthening the engaging ends, all companion pieces equipped the same.

51 is a flange shaped iron fastened to the ends of side box parts.

52 is an iron slide clasp firmly fastened 15 to the end-gate which holds the end-gates in position and when removing or replacing end-gates engages and slides upon flange 51. See Fig. 3.

53 is a key pin with a link joint, the link 20 being the size of rod passing through 52, end-gate and flange part of 51. The protruding end of link pin, when pin is in position, by gravity takes a position at right angles to the opening through which the 25 pin passes and thereby keeps the key pin in its proper position. See Fig. 3.

53 is a common chain fastened to key pin and end-gate. All key pins equipped the same.

30 From the foregoing description, taken in connection with the accompanying draw-

ings, the construction, operation, and advantages of my invention will be readily understood without requiring a more extended explanation.

35 Various changes in the form, proportion, and details of construction may be made within the scope of the invention without departing from the spirit or sacrificing any of the advantages thereof.

40 Having thus described my invention, what I claim and desire to secure by Letters Patent, is—

45 In a wagon body having each of its sides in three sections, the center sections with 45 ends fitted with slidable channels, sliding on the inner ends of the outer sections of sides, a set of brace irons, the basal portions fastened to the bolsters placed under the inner ends of the outer sections of sides of 50 box the upper portion of said set of brace irons fastened securely to the upper portions of the inner ends of the outer sections of sides of box.

55 In testimony whereof I have hereunto set my hand in the presence of two subscribing witnesses.

STEPHEN A. COVELL.

Witnesses:

HANNAH A. COVELL,
FREDA DAVIES.
